UNITED STATES PATENT OFFICE.

WALTER S. STEVENSON, OF PHILADELPHIA, PENNSYLVANIA.

DESIGN FOR A FRONT FOR HOT-AIR FURNACES.

SPECIFICATION forming part of Design No. 24,266, dated April 30, 1895.

Application filed February 21, 1895. Serial No. 539,287. Term of patent 7 years.

To all whom it may concern:

Be it known that I, WALTER S. STEVENSON, a citizen of the United States, residing in Philadelphia, Pennsylvania, have invented a new 5 and original Design for the Front of a Hot-Air Furnace, of which the following is a specification.

My design for the front of a stove is fully shown in the accompanying drawing, which 10 represents a face view of the same.

The design comprises a number of segregable features, namely, the top panel 1, the opposite side panels 2, 2, the fire door 3, the ash pit door 4, the poke hole door 5, and the 15 damper plate 6.

The essential features of ornamentation embodied in the unitary design are representations of streaming flames, flaming torches and lamps, and waved and crinkled ribbons, different combinations of these features being 20 found in each of the segregable features of the design.

The upper panel 1 has a central ornament consisting of the representation of a human 25 eye around which is the representation of a waved or crinkled ribbon with loose flowing ends, and extending in all directions from this ribbon, a representation of streaming flames.

Each of the side panels 2 has an ornament, 30 the representation of a flaming torch with a ribbon loosely twined around the handle of the same.

The fire door has a central circular damper opening, the upper portion of which is inclosed

by a panel having a surface representing 35 flames, and in each of the lower corners of the door is the representation of part of a flaming torch.

The main features of ornamentation of the ash pit door 4 are flaming antique lamps in 40 each of the upper corners of the same.

The poke hole door 5 has covers ornamented with rosettes and representations of flame bursting from each side of the same.

The damper plate 6 has representations of 45 flaming torches the handles of which cross each other and have a ribbon loosely twined about the same.

I claim—

1. The design for the front of a stove or furnace, substantially as shown and described. 50

2. In a design for the front of a stove or furnace, the design for the top panel, substantially as shown and described.

3. In a design for the front of a stove or furnace, the design for the side panel, substantially as shown and described. 55

4. In a design for the front of a stove or furnace, the design for the damper plate, substantially as described and shown. 60

In testimony whereof I have signed my name to this specification in the presence of two subscribing witnesses.

WALTER S. STEVENSON.
